UNITED STATES PATENT OFFICE.

GILBERT W. GOODRIDGE, OF BRIDGEPORT, CONNECTICUT, ASSIGNOR TO THE BRYANT ELECTRIC COMPANY, OF BRIDGEPORT, CONNECTICUT, A CORPORATION OF CONNECTICUT.

LAMP-GRIP.

1,208,543.

Specification of Letters Patent. Patented Dec. 12, 1916.

Application filed July 13, 1914. Serial No. 850,793.

To all whom it may concern:

Be it known that I, GILBERT W. GOODRIDGE, a citizen of the United States of America, and residing at Bridgeport, in the 5 county of Fairfield and State of Connecticut, have invented a certain new and useful Improvement in Lamp-Grips, of which the following is a specification.

My invention relates to lamp receptacles 10 and particularly to means for gripping the lamp to prevent its "backing out" due to its tendency to unscrew under the influence of vibration and the pressure under which it is screwed into the lamp.

15 In the accompanying drawings, Figure 1 is a broken side elevation of an electric lamp socket showing my invention embodied therein in one form; Fig. 2 is a perspective of the lamp gripping prongs shown in Fig. 1; 20 Fig. 3 is a perspective of a modified form of gripping prong; and Fig. 4 is a cross section showing the manner of its installation in a socket.

The present invention may be applied to 25 any type of lamp receptacle, but is here shown embodied in a lamp socket of known construction and comprising the usual cap 5 and shell 6 inclosing the insulating body 7, on which the wire terminals 8 and 9 are 30 mounted and carrying the screw shell terminal 10. The center contact is formed by the head 11 of the screw 12 and engages the center contact 13 of the plug base of the lamp 14. Surrounding the squared neck of 35 the screw bolt 12 and clamped beneath the latter I have arranged a lamp gripping element 15 in the form of a disk of heavy spring metal having wings 16 cut therefrom. These wings 16 are angled outwardly and 40 are offset at their ends to form prongs 17. Under normal conditions these prongs 17 extend beyond the center contact 11 so that when the lamp is screwed into the receptacle it first engages the prongs 17 and depresses 45 the latter against the action of the spring wings 16 until the center contact 13 of the lamp engages the center contact of the receptacle. The wings 16 are of sufficient strength to cause the prongs 17 to dig into 50 the entering end of the lamp, thus gripping the latter and holding it against reverse rotation.

To unscrew the lamp it is necessary to

apply sufficient force to overcome the resistance of the prongs 17. It is to be noted that 55 the wings 16 are so formed that while they yield during the insertion of the lamp, the direction of the reverse rotation of the latter is such as to cause them to act as struts which oppose the movement of the lamp. 60

The prongs may be formed in any suitable manner, as for instance (Figs. 3 and 4) by striking them from a ring 18 joined by spring loops 19 to a base plate 20 secured by the head 11 of the bolt 12 beneath the 65 wire terminal 9. When the lamp 14 is inserted, its center contact 13 engages the ring 18 and forces it down over the center contact 11, during which movement the prongs 17 dig into the end of the lamp base and thus 70 grip the latter and hold it against "backing out."

Various modifications of construction will readily suggest themselves and I do not limit myself to the details shown.

I claim as my invention:

1. A lamp receptacle having a screw connection with the inserted plug end of a lamp, and having a center contact, means for securing the latter in position in the receptacle 80 and a prong element independent of said center contact but held in position by said securing means and having a digging point shaped to permit the insertion of the plug end in the receptacle but entering the end of the plug to hold the latter against reverse rotation, substantially as described.

2. A lamp receptacle having a screw connection with the inserted plug end of a lamp, and having a center contact, means for securing the latter in position in the receptacle 90 and a prong element projecting beyond and independent of said center contact but held in position by said securing means and having a digging point shaped to permit the insertion of the plug end in the receptacle but entering the end of the plug to hold the latter against reverse rotation, substantially as described.

In testimony whereof I have signed my 100 name to this specification, in the presence of two subscribing witnesses.

GILBERT W. GOODRIDGE.
